PILE ELEVATOR

Leo C. Williams, Pearl River, N. Y., assignor to
 Dexter Folder Company, Pearl River, N. Y., a
 corporation of New York

Application February 6, 1948, Serial No. 6,781

8 Claims. (Cl. 271—62)

1

This invention relates to sheet handling apparatus and more particularly to pile elevators therefor which are employed to support and elevate a pile of sheets into position for feeding of the sheets manually or automatically one after another from the top of said pile.

One object of the present invention is to provide improved hydraulic pile elevator actuating mechanism which is simple and durable in construction, has a relatively small number of parts, requires less erecting and assembling time, and is fool-proof in operation.

Another object of the invention is to provide improved hydraulic pile elevator actuating mechanism wherein the fluid is conducted to the hydraulic cylinder to raise the pile elevator and is directed away from said cylinder to lower said elevator through a single conduit, thus reducing the number of conduits to a minimum.

Another object is to provide improved hydraulic pile elevator actuating mechanism including novelly arranged valve means for controlling the lowering of the pile elevator.

A further object is to provide improved hydraulic pile elevator actuating mechanism having fluid supplying pump means and fluid controlling valve means arranged and housed in a novel manner as a single unit and disposed wholly within the fluid supply to insure efficiency, low manufacturing, installation and maintenance costs, and fool-proof operation.

The above and further objects and novel features of the present invention will more fully appear from the following detail description when the same is read in connection with the accompanying drawings. It is to be expressly understood, however, that the drawings are for the purpose of illustration only, and are not intended as a definition of the limits of the invention, reference for this latter purpose being had primarily to the appended claims.

In the drawings, wherein like reference characters refer to like parts throughout the several views,

Fig. 1 is a front elevational view of a pile elevator and hydraulically actuated operating mechanism therefor embodying the present invention;

Fig. 2 is a vertical longitudinal sectional view on the line 2—2 of Fig. 1;

Fig. 3 is an enlarged front elevational view, partly in section, of the combined fluid reservoir, pump and control valve unit, shown in Figs. 1 and 2, for the hydraulic pile elevator actuating mechanism;

Fig. 4 is an enlarged vertical longitudinal sectional view of the fluid pump and control valve housing shown in Fig. 3; and

Fig. 5 is a fragmentary side elevation of the mechanism for manually controlling the lowering of the pile elevator.

2

The hydraulically actuated pile elevator as herein shown and hereinafter described is particularly adapted for supporting and elevating a pile of scored and slotted corrugated or fiber container blanks to the feeding in level of a container stitching or taping machine, at which level said blanks are hand folded and hand fed one after another to said stitching or taping machine for stitching or taping of the free ends or manufacturer's seam thereof. It is to be expressly understood, however, that said hydraulically actuated pile elevator is, as well understood in the art, equally adaptable for use in connection with hand or automatic feeding of all kinds and weights of sheet material such as, paper, cardboard, metal, wood, etc., to printing presses, coating and varnishing machines, slitters, punch presses, buffing and cleaning machines, and various other instrumentalities acting on such sheets.

Referring now to Figs. 1 and 2 of the drawings, the pile elevator and the hydraulically actuated operating mechanism therefor are mounted on a frame comprised by a pair of transversely spaced L-shaped side members indicated broadly at 5 and each preferably in the form of a flat steel plate having a vertically extending portion 6 and a horizontally extending portion 7. The side frame members 5 are supported on the machine foundation as by brackets 8 bolted or otherwise suitably secured thereto, and connected together by a channel cross beam 9 which is bolted or otherwise suitably secured to the upright portions 6 of said members near the lower ends thereof. The side frame members 5 are further connected 15 together by a vertically extending metal plate 10 that is bolted or otherwise suitably secured to the front sides of vertically extending channel members 11 which, in turn, are bolted or otherwise suitably secured to said side frame members on the inner sides thereof. Spaced rearwardly from the plate 10, as by spacers 12, and bolted or otherwise suitably secured to said plate is another plate 13 against which the front side of a pile or supply of container blanks or other sheets 14 bears during elevation of the same by mechanism to be hereinafter described.

The pile of container blanks or other sheets 14 is supported on a pile elevator comprised by a pair of transversely spaced L-shaped side members indicated broadly at 15 and each is preferably in the form of a flat steel plate having a vertically extending portion 16 and a horizontally extending portion 17. The elevator side members 15 are connected together at the front and rear thereof by transversely extending channel members 18 which are bolted or otherwise suitably secured thereto. The channel members 18 have journaled therein rollers 19 on which the pile of container blanks or other sheets 14 may be 20 freely moved into proper position on the elevator.

Accordingly, the pile of container blanks or other sheets 14 is preferably placed on a pile board 20 and the latter and pile are then run on the elevator from either side thereof when said elevator is lowered to loading position as hereinafter described. The elevator is guided for vertical movement by rollers 21 which are journalled in spaced relation on the elevator side members 15 and arranged to run in the channel members 11.

The pile elevator and pile of container blanks 10 or other sheets 14 thereon are intermittently raised by hydraulically actuated mechanism to maintain the top of the pile at a proper feeding level. This mechanism is preferably mounted and constructed as follows. Connected with one 15 of the elevator side members 15 as at 22 is one end of a cable 23 which extends upwardly and forwardly around a suitably grooved sheave 24. This sheave 24 is journalled on a pin 25 which is fixed in a block 26 and extends laterally therefrom through the adjacent channel member 11 and the upright portion 6 of the adjacent side frame member 5. The block 26 is welded or otherwise suitably secured to the upper end of an angle iron 27 which is spaced from the adjacent side 20 frame member 5, as by a spacer 28, and bolted or otherwise suitably secured to the plate 10.

From the sheave 24 the cable 23 extends downwardly to the channel cross beam 9 at which point said cable passes under and around a suitably grooved sheave 29 through a suitable opening formed in said cross beam and into which the latter sheave projects. The sheave 29 is journalled on a pin 30 which is secured in any suitable manner in the channel cross beam 9. From the sheave 29 the cable 23 extends transversely beneath the channel cross beam 9 and above a horizontally arranged hydraulic cylinder 31, and then passes around a suitably grooved sheave 32 and back to said cylinder to which the opposite free end of said cable is then anchored in any suitable manner. The hydraulic cylinder 31 is bolted or otherwise suitably secured to the channel cross beam 9 on the underside thereof and is provided with a hydraulically actuated piston rod or ram 33 projecting outwardly through one end of said cylinder. The sheave 32 is journalled as at 34 on a yoke 35 which is secured in any suitable manner on the outwardly projecting end of the piston rod or ram 33.

Connected with the other elevator side member 15 in the same manner as cable 23 is one end of a cable 37 which extends upwardly and forwardly around a suitably grooved sheave 38. This sheave 38 is journalled on a pin 39 which is fixed in a block 40 and extends laterally therefrom through the adjacent channel member 11 and the upright portion 6 of the adjacent side frame member 5. The block 40 is welded or otherwise suitably secured to the upper end of an angle iron 41 which is spaced from the adjacent side frame member 5, as by a spacer 42, and bolted or otherwise suitably secured to the plate 10. From the sheave 38 the cable 37 extends downwardly to the channel cross beam 9 at which point said cable passes under and around a suitably grooved sheave 43. This sheave 43 is journalled on a pin 44 which is secured in any suitable manner in blocks 45 that are disposed on opposite sides of said sheave and welded or otherwise suitably secured to the channel cross beam 9.

From the sheave 43 the cable 37 extends transversely along the upper side of the channel cross beam 9 and then passes over and around the 75

sheave 29 which is suitably grooved to also receive said cable. From the sheave 29 the cable 37 extends back over the hydraulic cylinder 31 and beneath the channel cross beam 9, and then passes around the sheave 32 and back again to said cylinder to which the free opposite end thereof is then anchored in any suitable manner, the sheave 32 being suitably grooved to also receive said cable. It will thus appear that when the piston rod or ram 33 is hydraulically advanced toward the right as viewed in Fig. 1, corresponding movement will be imparted to the yoke 35 and sheave 32, and those portions of the cables 23 and 37 extending from the hydraulic cylinder 31 around the sheave 32 and to the sheave 29 will be lengthened. This obviously shortens those portions of the cables 23 and 37 between the elevator side members 15 and the sheaves 24 and 38 resulting in raising of the elevator and pile 14 thereon. The piston rod or ram 33 is guided for right line movement by a pair of rods 46 which are slidably engaged by the yoke 35 and have opposite extremities thereof secured on the hydraulic cylinder 31 and in a block 47 that is welded or otherwise suitably secured to the underside of the channel cross beam 9. It is to be understood that any suitable means other than a cable connection between the piston rod or ram 33 and the elevator is contemplated.

Delivery of fluid under pressure into the hydraulic cylinder 31 to intermittently advance the piston rod or ram 33 and thereby intermittently raise the elevator and pile of container blanks or other sheets thereon, and the release of said fluid from said cylinder to permit lowering of the elevator for loading and reloading purposes is, in accordance with the present invention, effected and controlled by improved pump and valve means preferably mounted, constructed, arranged and operated as follows. Secured to the channel cross beam 9 through the medium of brackets 48 is a small platform 49 (Figs. 1 and 2) having welded or otherwise suitably secured thereto a receptacle or tank 50 which is closed at the top thereof by a cover 51 bolted thereto. The receptacle or tank 50 is adapted to contain a supply of oil as indicated at 52 (Fig. 3) which is introduced therein through a suitable opening 53 formed in the cover 51 for this purpose. Connected with the cover 51, as by a fitting 54, and communicating with the interior of the receptacle or tank 50 through a suitable opening 55 formed in said cover is one end of a conduit 56 the opposite end of which is connected with the hydraulic cylinder 31 at the left hand end thereof as viewed in Fig. 1.

Threaded in the opening 55 in cover 51, as by a fitting 57, and communicating with the conduit 56 is one end of a conduit 58 (Fig. 3) which is disposed wholly within the fluid supply tank or receptacle 50. The opposite end of this conduit 58 is connected, as by a fitting 59, with the housing 60 of a combined fluid supplying pump and fluid controlling valve unit indicated broadly at 61 which, as herein shown, is also disposed within the tank 50 and wholly submerged in the fluid 52 in said tank. The pump and valve unit 61 may be supported in various ways in the tank 50 but, as herein shown, said unit is preferably bolted or otherwise suitably secured to the lower end of a depending bracket 62 which is secured to or formed integrally with the cover 51.

Referring now more particularly to Fig. 4 of the drawings, the housing 60 of the pump and valve unit 61 has formed therein at one side

thereof a fluid inlet port 63 which opens outwardly into the fluid supply 52 and inwardly into a cylindrical bore 64 in said housing. Slidably mounted in the cylindrical bore 64 in housing 60 is a fluid controlling valve 65 provided with a reduced portion 66 for establishing communication at certain intervals between the port 63 and a passage 67. This passage 67 is formed in the housing 60 preferably in line with the port 63 and connected with a passage 68 through a port 69. The passage 68 in housing 60 communicates with a chamber 70 formed by the lower end of a bushing 71 fixed in a cylindrical bore 72 in said housing, and the upper end of a plug 73 which is threaded in said bore, said communication being established through a suitable opening 74 formed in the lower end of the bushing 71. Formed in the housing 60 and preferably in line with the chamber 70 is a passage 76 having one end opening into said chamber and the opposite end closed by a plug 77. This passage 76 is connected with a passage 78 through a port 79. Passage 78 has one end thereof closed by the bushing 71 and the opposite end opening into a cylindrical bore 165 formed in housing 60. This bore 165 communicates with the conduit 58 through a fluid outlet port 166 formed in the end wall of housing 60 and in which the fitting 59 of conduit 58 is threaded. Bore 165 also communicates with the fluid supply 52 through a port 167 formed in the end wall of housing 60 below port 166 and having threaded therein a pipe fitting 168 to direct the fluid from bore 165 downwardly into the fluid supply 52, as hereinafter described.

Slidably mounted in the cylindrical bore 165 in housing 60 is a second fluid controlling valve 169 provided with a reduced portion 170 for establishing communication between passage 78 and port 166 in one position of said valve, and between said passage, said port and port 167 in another position of the valve, as hereinafter described. Valve 169 is normally disposed in the full line position shown in Fig. 4 which is the position it occupies for raising of the elevator and pile of container blanks or other sheets thereon, and when said elevator and pile are in raised position and while said blanks or other sheets are being fed from the top of the pile. In this position of valve 169 it will be noted that port 167 is closed by the lower large end of said valve, and that the passage 78 is open only to the fluid outlet port 166 through the bore 165 and the reduced portion 170 of the valve. Under these conditions fluid under pressure forced into bore 165 through passage 78, as hereinafter described, cannot return to the fluid supply 52 through port 167, but can flow into the hydraulic cylinder 31 through port 166 and conduits 58, 57 and thereby effect actuation of piston rod or ram 33 and raising of the pile elevator and pile of container blanks or other sheets thereon. Since the fluid return port 167 is normally closed or blocked by valve 169 as above described, the fluid in cylinder 31 cannot return therefrom to the fluid supply 52 through said port.

Fitted for reciprocation in the bore 80 of bushing 71 is a plunger pump 81 which projects upwardly through the housing and is provided on the upper end thereof with an enlarged head portion 82. The plunger pump 81 is continuously reciprocated by mechanism preferably mounted, constructed and operated as follows. Bolted or otherwise suitably secured to the platform 49 is an electric motor 83 (Figs. 1, 2) con-

nected with a suitable source of current and controlled for starting and stopping purposes by suitable switch means (not shown). Fixed on the armature shaft 84 of electric motor 83 is a pulley 85 around which passes a belt 86 that also passes around and drives a pulley 87. This pulley is fixed on and drives a short crank shaft 88 (Fig. 3) which extends through a suitable opening 89 formed in the rear side of the fluid supply tank or receptacle 50, and is journaled in a suitable bearing in the depending bracket 62. Pivotedly connected as at 90 with the crank shaft 88 is the upper end of a connecting rod 91, the lower end of which is pivotally connected as at 92 with the head portion 82 of the plunger pump 81. It will thus appear that the plunger pump 81 through the described driving connections therefor with the electric motor 83 will be operated continuously and raised and lowered out of and into the chamber 70 during each revolution of the crank shaft 88.

Under these conditions, and with the fluid controlling valves 65 and 169 raised to the full line positions thereof shown in Fig. 4, the fluid 25 52 is intermittently drawn from the tank or receptacle 50 through the port 63, bore 64, the reduced portion 66 of the valve 65, the passage 67, the port 69, the passage 68, the opening 74, and into the chamber 70. Fluid so drawn into 30 the chamber 70 is then forced therefrom by the plunger pump 81 through the passage 76, the port 79, the passage 78, bore 165, the reduced portion 170 of valve 169, the port 166, the conduits 58, 56, and into the left hand end of the 35 hydraulic cylinder 31 (Fig. 1), resulting in step by step movement of the piston rod or ram 33 toward the right and intermittent raising of the pile elevator and pile of container blanks or other sheets thereon. When the fluid controlling valve 65 is lowered to the dotted line position 40 thereof shown in Fig. 4, said valve closes the fluid inlet port 63, thus disconnecting the fluid supply 52 from the plunger pump 81 so that no fluid can be drawn by said pump into the chamber 70 as described upon continued action thereof. In this manner the plunger pump 81 is rendered ineffective to supply fluid into the hydraulic cylinder 31 with the result that no further upward movement is imparted to the pile 45 elevator and pile of container blanks or other sheets thereon.

It will therefore be noted that through arrangement of the fluid controlling valve 65 between the fluid supply 52 and the plunger pump 81, by-passing of the fluid is unnecessary to enable continuous operation of said pump without imparting raising movement to the pile elevator and pile of container blanks or other sheets thereon, thereby enabling the use of a fluid controlling valve much simpler in construction and requiring less power to operate. It will further be noted that arrangement and operation of the plunger pump 81 and the fluid controlling valves 65 and 169 in the fluid supply 52 insures that no air is drawn into the hydraulic system, eliminates packing, and provides lubrication for said pump and said valves.

To prevent return flow of fluid from the hydraulic cylinder 31 through the conduits 56 and 58, bore 165, and passage 78, and consequently dropping of the elevator and pile of container blanks or other sheets thereon, the housing 60 has incorporated therein an upwardly opening check valve preferably in the form of a ball 93 (Fig. 4) which is adapted to drop and

close the end of the port 79 opening into the passage 78 when no fluid under pressure is being forced through said port by the plunger pump 81. The fluid previously admitted into the cylinder 31 to intermittently raise the pile elevator and pile of container blanks or other sheets thereon is then trapped therein, thus maintaining the elevator and pile in raised position. The ball check valve 93 is retained in a valve cage 94 which is threaded in a suitable opening in the housing 60 and provided with a plurality of fluid passages or ports 95.

To prevent return flow of fluid from the chamber 70, the housing 60 has incorporated therein an upwardly opening check valve preferably in the form of a ball 96 which is adapted to drop and close the end of the port 69 opening into the passage 68 on the pressure stroke of the plunger pump 81. The ball check valve 96 is retained in a valve cage 97 which is threaded in a suitable opening in the housing 60 and provided with a plurality of fluid passages or ports 98.

In order to guard against overloading of the pile elevator which would result in breaking of the cables 23, 37 and damage to said elevator and the hydraulic mechanism, the plug 73 has formed therein a relief port 99 (Fig. 4) having one end opening into the chamber 70 and the opposite end opening into a passage 100 also formed in said plug. This passage 100 opens into the fluid supply 52 through a tubular adjusting screw 101 threaded in plug 73. The relief port 99 is normally closed by a downwardly opening pressure relief valve disposed within the passage 100 and preferably in the form of a ball 102 which is held against the port 99 by a compression spring 103 interposed between said ball and the adjusting screw 101. The tension of the spring 103 on the ball relief valve 102 is so regulated by the adjusting screw 101 that the fluid pressure required to effect elevation of the maximum load capable of being handled on the elevator is not sufficient to cause opening of said valve. Should, however, the fluid pressure exceed a predetermined amount due to overloading of the pile elevator or for any other reason, the relief valve 102 is caused to open and permit the fluid to flow from the chamber 70 back into the fluid supply 52 through the relief port 99, the passage 100 and the adjusting screw 101, thus preventing actuation of the piston rod or ram 33 and raising of the pile elevator and pile of container blanks or other sheets thereon. The desired adjustment of screw 101 may be effected without removing housing 60 from the fluid supply tank 50, and for this purpose the platform 49 is provided with a suitable opening 104 communicating with the interior of said tank and adapted to receive a screw driver or other similar tool. Opening 104 is normally closed by a removable drain plug 104' threaded therein.

It will be noted that arrangement of the fluid controlling valves 65, 109, the plunger pump 81, the fluid check valves 93 and 96, and the safety pressure relief valve 102 in the housing 60 as a single unit materially simplifies the hydraulic system and insures low manufacturing cost and fool-proof operation of the hydraulic mechanism.

As hereinbefore stated, the fluid controlling valve 65 is raised and lowered to render the plunger pump 81 effective and ineffective to supply fluid into the hydraulic cylinder 31, and while this may be accomplished in any suitable manner and by any suitable means for this purpose, said operation, as herein shown, is preferably effected

5 by electrically actuated means controlled by switch means responsive to variations in the height of the pile of container blanks or other sheets on the elevator. The contacts of the switch are normally open until a sufficient number of sheets have been fed from the top of the pile, whereupon the switch closes under the control of the pile to actuate the electrical means, thereby raising the fluid controlling valve 65 and rendering the plunger pump 81 effective to supply fluid under pressure into the hydraulic cylinder 31 to intermittently raise the elevator and pile of container blanks or other sheets thereon. Upon raising of the elevator and pile of container blanks or other sheets thereon, the switch is again opened by the pile and opening of the switch controls the lowering of the fluid controlling valve 65 to render the plunger pump 81 ineffective to further raise the elevator and pile thereon. Said electrically actuated means and pile controlled switch means are preferably mounted, constructed and operated as follows.

Bolted or otherwise suitably secured to the cover 51 of the fluid supply tank or receptacle 50 is a bracket 105 (Fig. 3) to which is bolted or otherwise suitably secured a solenoid 106 having a core 107. Pivotedly connected as at 108 with the lower end of the core 107 of solenoid 106 is the upper end of a rod 109 which extends downwardly into the tank or receptacle 50 through a suitable opening formed for this purpose in the cover 51 and has its lower end pivotally connected as at 110 with the upper end of the fluid controlling valve 65.

Bolted or otherwise suitably secured to the angle iron 27 near the top thereof and projecting inwardly therefrom is a square bar 111 (Figs. 1 and 2). Engaged over and slideable along the bar 111 is a block 112 which is held against displacement from said bar by a plate 113 that is bolted or otherwise suitably secured on the upper side of said block. The block 112 and parts carried thereby hereinafter described may be adjusted along the bar 111 in accordance with variations 40 in width of the container blanks or other sheets being handled on the elevator and may be secured in any desired position of adjustment by any suitable known means, such as a thumb screw or the like threaded in block 112.

Secured in any suitable manner to the underside of block 112 is a plate 115 having a downwardly bent side portion 116 (Fig. 1). Bolted or otherwise suitably secured to plate 115 is a normally open switch 117 which is of a known type having a pair of spaced stationary contact members and a movable contact member which is adapted to bridge said stationary contact members and thereby complete the electrical circuit to solenoid 106. The movable contact member has connected therewith a short actuating arm 121 which is normally biased to open circuit position by a light pull spring 122 having one end connected with said arm and the opposite end connected to a strip 123 secured to the casting of switch 117.

Pivotedly mounted as at 124 (Fig. 2) to swing in a vertical plane on the side portion 116 of plate 115 is a lever 127 having one end engaged 70 with the contact actuating arm 121. Pivotedly mounted at 128 on the opposite end of lever 127 to swing in a horizontal plane is an arm 129 to which is secured a feeler 130 that extends rearwardly and downwardly and also inwardly at an angle into engagement with the top of the pile

75

of container blanks or other sheets 14 at one side and adjacent the front thereof. Feeler 130 is yieldably held in its original angular pile engaging position by a light pull spring 131 having one end connected to lever 127 and the opposite end connected to a stop lug formed on arm 129. The purpose of the double-jointed feeler 130 is to enable the same to yield inwardly and upwardly in horizontal and vertical directions when handling container blanks and the opposite side portions of the top blank are folded inwardly toward each other on the pile prior to feeding of said blank into the stitching or taping machine, thus presenting no interference to the blank folding operation.

It will be understood that the switch 117 and actuating means therefor including the feeler 130 may be arranged in a well-known manner to operate on the rear of the pile 14 instead of on the front of said pile as herein shown, and that the feeler 130 may be operated at predetermined intervals in a well known manner into and out of engagement with the top of the pile 14. It will also be understood that the horizontal swinging movement of the feeler 130 and the inward angular position of said feeler may be eliminated when the pile elevator is employed in connection with hand or automatic feeding of container blanks or other sheets that are not folded prior to feeding of the same, in which event the feeler 130 may be secured to or formed integrally with the arm 127.

The solenoid 106 and one of the stationary contact members of switch 117 have connected therewith lead wires 133 and 134, respectively, which are connected with a suitable source of electric current (Fig. 2). The other stationary contact member and the solenoid 106 are connected together by a wire 135 so that when the movable contact member is lowered into engagement with both of the spaced stationary contact members the electric circuit for the solenoid 106 will be completed.

Assuming now that the top of the pile 14 is disposed at the normal feeding level at which time the switch 117 is open, the fluid controlling valve 65 is in its lowered dotted line position shown in Fig. 4 closing the fluid inlet port 63, and the fluid controlling valve 169 is in its raised full line position. Under these conditions the plunger pump 81 idly reciprocates without pumping fluid, no upward movement is imparted to the elevator and pile of container blanks or other sheets thereon, and said elevator and pile are held in raised position as hereinbefore described. As the container blanks or other sheets are fed one after another from the top of the pile, however, the feeler 130 will lower by gravity so that when a sufficient number of said blanks or sheets have been so fed, switch 117 will be closed, thus completing the electric circuit for the solenoid 106. The solenoid 106 is then energized and draws the core 107 upwardly, thereby raising the fluid controlling valve 65 to the full line position thereof shown in Fig. 4. Under these conditions the fluid inlet port 63 is opened, and upon continued reciprocation of the plunger pump 81 fluid is drawn from the supply 52 and delivered under pressure into the hydraulic cylinder 31 as hereinbefore described, thus raising the elevator and pile of container blanks or other sheets thereon.

As the pile thus raises, the feeler 130 engaged with the top of the pile also raises causing switch 117 to open. Opening of the switch 117 de-energizes the solenoid 106 whereupon the fluid con-

trolling valve 65 drops such as by gravity to the dotted line position thereof shown in Fig. 4, thus again closing the fluid inlet port 63 and rendering the plunger pump 81 ineffective as hereinbefore described to further raise the elevator and pile of container blanks or other sheets thereon.

Lowering of the fluid controlling valve 65 as aforesaid to stop further raising of the elevator and pile of container blanks or other sheets thereon is delayed or retarded so that, upon opening of the switch 117, raising of the elevator will not be directly stopped but, on the contrary, will continue to raise the pile an amount sufficient to enable feeding of a number of blanks or sheets from the top thereof before raising of the elevator and said pile is again necessary. In this manner the pile is raised to the normal feeding range upon a single operation of the switch 117, whereas the switch would otherwise operate for each sheet particularly if they are relatively thick, thus eliminating frequent operations of said switch, preventing excessive wear of the same and frequent repairs or replacements thereto.

The feeler 130 and its associated devices switch 117, solenoid 106, and fluid controlling valve 65 constitute supply control means and various ways and means may be employed in connection with any part thereof to delay or retard the operation of the same whereby delay in the lowering movement of the fluid controlling valve 65 is effected. Preferably, such delaying means is associated with the fluid controlling valve 65 and preferably too is effected by fluid means which may be constructed and arranged as follows. Formed in the housing 60 at the side thereof having the fluid inlet port 63 and spaced from said port is a restricted port 136 (Fig. 4) having one end opening into the fluid supply 52 and the opposite end opening into the bore 64. The bore 64 is closed at the lower end thereof by a plug 137 having an open ended port 138 therein communicating with the fluid supply 52 and with said bore. The port 138 is normally closed by an upwardly opening check valve preferably in the form of a ball 139. The lower end of the fluid controlling valve 65 is countersunk as at 140 to receive the ball 139 when said valve is lowered.

It will thus appear that when the fluid controlling valve 65 is raised to effect raising of the elevator and pile of container blanks or other sheets thereon as hereinbefore described, said raising of said valve creates vacuum in the lower end of the bore 64 whereupon the ball check valve 139 is raised by the fluid pressure on the underside thereof, thus permitting the fluid 52 to flow into said bore through the port 138. When the switch 117 is opened as hereinbefore described, and the fluid controlling valve 65 begins to drop by gravity, at which time the port 138 is again closed through dropping of the ball check valve 139, the fluid previously admitted into the bore 64 must be forced therefrom by the fluid controlling valve 65 through the restricted port 136 and back into the supply 52 before said valve can drop to the dotted line position thereof shown in Fig. 4, thus materially retarding or delaying the lowering movement of the fluid controlling valve 65.

When the pile of container blanks or other sheets is exhausted through intermittent raising of the elevator and feeding of said blanks or sheets one after another therefrom, the elevator may be quickly lowered to the machine foundation to receive a new pile of blanks or other sheets. This lowering of the elevator is

under the control of the fluid controlling valve 169 and is effected by simply lowering said valve from its normal full line position to its broken line position shown in Fig. 4. As herein shown, valve 169 is manually raised and lowered by mechanism constructed and mounted as follows. Bolted or otherwise suitably secured to the channel members 11 on the tops thereof are blocks 141 (Figs. 1 and 2) in which is journalled opposite extremities of a transversely extending rock shaft 142 having fixed thereon a handle 143. Fixed on one end of the rock shaft 142 is an arm 144 having pivotally connected therewith as at 145 the upper end of a rod 146 the lower end of which is pivotally connected as at 147 (Fig. 5) with an arm 148. This arm 148 is fixed on a transversely extending rock shaft 149 having one end thereof extending through a suitable opening formed in one of the side frame members 5 and journalled in a suitable bearing in a bracket 150 that is bolted or otherwise suitably secured to said side frame member.

The opposite end of shaft 149 is journalled in a suitable bearing provided in a bracket 151 which is bolted or otherwise suitably secured to the cover 51 of the fluid supply tank or receptacle 50. Secured to shaft 149 adjacent bracket 151 is an arm 152 to the free end of which is pivotally connected the upper end of a connecting rod 153 that extends downwardly into the tank or receptacle 50 through a suitable opening formed in the cover 51. The lower end of rod 153 is pivotally connected as at 154 to the upper end of the fluid controlling valve 169. Rocking movement of shaft 149 in opposite directions to raise and lower valve 169 is limited by stop screws 155 and 156 which are engaged by arm 148 and are adjustably threaded in the adjacent side frame member 5 and the bracket 150, respectively.

While the container blanks or other sheets are fed from the top of the pile and intermittent raising of the elevator and said pile is effected by the plunger pump 81, the handle 143 is disposed in the raised position thereof shown in Fig. 2, and the arm 143 is disposed in engagement with the stop screw 155 (Fig. 5). Under these conditions the valve 169 is raised to the full line position shown in Fig. 4 so that the fluid forced into bore 165 by the plunger pump 81 will flow into the hydraulic cylinder 31 and thereby effect raising of the elevator and pile of container blanks or other sheets thereon as hereinbefore described. When the pile of container blanks or other sheets is exhausted, however, the elevator may be quickly lowered to the machine foundation by moving the handle 143 downwardly (Fig. 2) until the arm 148 through the described connections therefor with said handle is raised into engagement with the stop screw 156, thus rocking the shaft 149 and lowering valve 169 to the broken line position shown in Fig. 4, whereupon the fluid outlet passage 78 and the fluid outlet port 166 are connected with the fluid supply 52 through the bore 165, the reduced portion 170 of valve 169 and the fluid return port 167. Under these conditions the fluid in the hydraulic cylinder 31 is released and the elevator drops by gravity to the machine foundation. As the elevator thus drops by gravity, the fluid in the hydraulic cylinder 31 is forced therefrom back into the tank or receptacle 50 through the conduits 56, 58, the port 166, the housing 60 and the port 167, the resistance created by the fluid in passing through said conduits, said ports and said

housing controlling the rapidity of the downward movement of the elevator.

When the elevator is rapidly lowered to the machine foundation as aforesaid, the plunger pump 81, through lowering of the feeler 130, closing of switch 117 and raising of the valve 65 thereby, will supply fluid into the bore 165 in housing 60, said fluid, however, upon entering said bore will flow out again and back into the tank or receptacle 50 through the opened return port 167, thus preventing raising of the elevator while a new pile of container blanks or other sheets is being loaded thereon. It will be understood that when the elevator is lowered to the machine foundation for loading or re-loading purposes the plunger pump 81 may be stopped by stopping the electric motor 83 in the usual manner.

The elevator having been lowered to the machine foundation and a new pile of container blanks or other sheets having been properly loaded thereon in the usual manner from either side thereof, said elevator and the new pile are then raised until the top of said pile is brought into proper position for feeding of the blanks or other sheets one after another therefrom. For this purpose, the handle 143 is again raised to its normal position (Fig. 2) to lower the rod 146 and arm 148 until the latter engages the stop screw 155, thus rocking the shaft 149 in the opposite direction and again raising valve 169 to the full line position shown in Fig. 4. Thereupon, the fluid return port 167 in housing 60 is again closed by valve 169, and the fluid forced into the bore 165 by plunger pump 81 will flow therefrom into the hydraulic cylinder 31 as hereinbefore described and effect raising of the elevator and the new pile of container blanks or other sheets thereon until the top of said pile reaches the normal feeding level.

As the new pile thus raises, the top of said pile engages and raises the feeler 130, thereby opening the switch 117. The fluid controlling valve 65 then drops slowly by gravity as hereinbefore described, during which time raising of the elevator and pile continues until the top of the pile reaches the normal feeding level, whereupon the fluid inlet port 63 is again closed by said valve and the elevator is stopped. Feeding of the container blanks or other sheets one after another from the top of the new pile may now be resumed and continued through intermittent raising of the elevator and pile controlled by the feeler 130. The folded container blanks are fed one after another into the stitching or taping machine over an upwardly and forwardly extending plate 159 which forms part of said machine.

If desired, the fluid controlling valve 169, like the fluid controlling valve 65, may be electrically operated by a solenoid similar to the solenoid 106 and controlled by a suitable push button switch conveniently placed on the floor or on the machine frame for foot or hand operation by the operator.

It will be apparent that should the switch 117, for any reason, fail to render the plunger pump 81 ineffective through the described means for this purpose when the pile of container blanks or other sheets is completely exhausted, the hydraulic mechanism, if allowed to continue in operation, would raise the elevator beyond the normal feeding level and cause damage to the switch 117 and component parts thereof, and also pos-

sible damage to the hydraulic mechanism. Means is, therefore, provided independent of the switch 117 to stop the elevator when said elevator reaches a predetermined elevated position. Said means stops the plunger pump 81, and, as herein shown, is preferably comprised by a normally closed switch 160 (Fig. 1) which is arranged in a well known manner in the electric circuit for the electric motor 83. This switch 160 is bolted or otherwise suitably secured to one of the channel members 11 near the top thereof and is provided with an actuating arm 161 that extends into the path of upward movement of one of the elevator side members 15 (Fig. 2). The switch 160 is so located on the channel member 11 that the arm 161 thereof will be engaged by the elevator side member 15 before the elevator is raised an amount sufficient to cause damage to the switch 117 and possible damage to the hydraulic mechanism.

It will thus appear that should the switch 117, for any reason, fail to render the plunger pump 81 ineffective through the described means for this purpose, the elevator upon continued upward movement thereof will engage and raise the arm 161 of switch 160 and thus open said switch. Opening of the switch 160 breaks the circuit to the electric motor 83, thus stopping said motor and further operation of the plunger pump 81 thereby. Stopping of the plunger pump 81 throws the hydraulic mechanism out of operation and prevents further raising of the elevator. When the elevator is rapidly lowered as hereinbefore described to reload it with a pile of container blanks or other sheets, the arm 161 of switch 160 returns to its original position and closes said switch, thus again starting the motor 83 to enable raising of the elevator and new pile of container blanks or other sheets thereon as hereinbefore described.

It will be noted that the cover 51 for the tank or receptacle 50 supports the pump and valve unit 61, the pump operating mechanism, the check and relief valves 93, 96, 102, the solenoid 106, the bracket 151 and the conduits 56 and 58, all of which may be bench assembled, thus reducing elevator erecting time.

It will further be noted that by virtue of the novel arrangement of the fluid controlling valve 169 with respect to the pump 81 and the hydraulic cylinder 31, and the mounting of said valve in the housing 69 together with said pump and the fluid controlling valve 65, a single conduit is only required to conduct the fluid to the cylinder and to direct said fluid away from said cylinder, thus eliminating the use of separate return flow conduits, and the various operating and control members of the hydraulic system are contained in a single and simple compact unit which requires less space and may be located relatively close to the hydraulic cylinder, thus further simplifying the construction and operation of the hydraulic pile elevator actuating mechanism.

The present description and its accompanying drawings set forth with more or less particularity one embodiment of the present invention, but it is to be expressly understood that said invention is not limited to said embodiment or otherwise than by the terms of the appended claims.

What is claimed is:

1. In apparatus of the type having means for supporting a pile of sheets to be fed one after another from the top thereof, and hydraulic mechanism including a cylinder for elevating said

pile supporting means, the combination of a receptacle adapted to contain a supply of fluid, pump means in said receptacle for supplying said fluid into said cylinder, valve means in said receptacle and submerged in the fluid therein, said valve means being movable to one position to enable delivery of said fluid into said cylinder by said pump means and movable to another position to interrupt said delivery of said fluid into said cylinder, pile engaged means controlling the operation of said valve means, other valve means in said receptacle and submerged in the fluid therein, said other valve means being movable to one position to permit said delivery of said fluid under pressure into said cylinder and movable to another position to simultaneously connect both said cylinder and said pump means with said fluid supply, and means for moving said other valve means.

2. In apparatus of the type having means for supporting a pile of sheets to be fed one after another from the top thereof, and hydraulic mechanism including a cylinder for raising said pile supporting means, the combination of a receptacle adapted to contain a supply of fluid, a housing in said receptacle and wholly submerged in the fluid therein, a continuously reciprocating plunger pump in said housing for supplying fluid from said fluid supply through said housing and into said cylinder, a valve in said housing and disposed between said pump and said cylinder, said valve being movable to one position to permit said pump to supply said fluid under pressure into said cylinder and movable to another position to permit return flow of fluid simultaneously from both said cylinder and said pump to said fluid supply, means for operating said valve, and a check valve in said housing between said pump and said first-named valve.

3. In apparatus of the type having means for supporting a pile of sheets to be fed one after another from the top thereof, and hydraulic mechanism including a cylinder for raising said pile supporting means, the combination of a receptacle adapted to contain a supply of fluid, a housing in said receptacle and wholly submerged in the fluid therein, a continuously reciprocating plunger pump in said housing for supplying fluid from said fluid supply through said housing and into said cylinder, a pile controlled first valve in said housing between said pump and said fluid supply and movable to connect the latter with and disconnect the same from said pump, a check valve in the housing between said first valve and said pump, a second valve in said housing between said pump and said cylinder, said second valve being movable to one position to permit said pump to supply said fluid under pressure into said cylinder and movable to another position to permit return flow of fluid simultaneously from both said pump and said cylinder through said housing into said fluid supply, means for operating said second valve, and a check valve in said housing between said pump and said second valve.

4. In apparatus of the type having means for supporting a pile of sheets to be fed one after another from the top thereof, and hydraulic mechanism including a cylinder for raising said pile supporting means, the combination of a receptacle adapted to contain a supply of fluid, a cover for said receptacle, a housing carried by said cover and wholly submerged in the fluid in said receptacle, a plunger pump in the housing for supplying fluid from said fluid supply through said housing and into said cylinder, driven means

on said cover for continuously reciprocating said plunger pump, a first valve in said housing between said pump and said fluid supply and movable to connect the latter with and disconnect the same from said pump, pile controlled means on said cover controlling the operation of said first valve, a second valve in said housing between said pump and said cylinder, said second valve being movable to one position to permit said pump to supply said fluid under pressure into said cylinder and movable to another position to permit return flow of fluid simultaneously from both said pump and said cylinder through said housing into said fluid supply, and means on said cover for operating said second valve.

5. In apparatus of the type having means for supporting a pile of sheets to be fed one after another from the top thereof, and hydraulic mechanism including a cylinder for raising said pile supporting means, a pump and valve assembly comprising, a receptacle adapted to contain a supply of fluid, a housing in said receptacle and wholly submerged in the fluid therein, said housing having a fluid inlet port, a fluid outlet port and a fluid return port, a plunger pump in the housing and continuously reciprocated to draw fluid from said supply into said housing through said inlet port and force said fluid therefrom into said cylinder through said outlet port and into said fluid supply through said return port, a valve in said housing and disposed between said plunger pump and said fluid outlet and return ports, said valve being movable to one position to close said return port and connect said pump with said outlet port, thereby causing said fluid to be delivered by said pump into said cylinder, and movable to another position to open the return port and connect said pump and said outlet port with said return port, thereby permitting return flow of fluid from said cylinder and said pump to said fluid supply, means for operating said valve, and a check valve in said housing between said plunger pump and said first-named valve.

6. In apparatus of the type having means for supporting a pile of sheets to be fed one after another from the top thereof, and hydraulic mechanism including a cylinder for raising said pile supporting means, a pump and valve assembly comprising, a receptacle adapted to contain a supply of fluid, a housing in said receptacle and wholly submerged in the fluid therein, said housing having a fluid inlet port, a fluid outlet port and a fluid return port, a plunger pump in said housing and continuously reciprocated to draw fluid from said fluid supply into said housing through said inlet port and force said fluid therefrom into said cylinder through said outlet port and into said fluid supply through said return port, a pile controlled valve in said housing and disposed between said plunger pump and said fluid inlet port and reciprocal to connect the latter with and disconnect the same from said pump, a second valve in said housing and disposed between said plunger pump and said fluid outlet and return ports, said second valve being movable to one position to connect said plunger pump with said fluid outlet port and movable to another position to simultaneously connect said outlet port and said plunger pump with said return port, means for moving said second valve, and check valves in said hous-

ing and disposed between said pile controlled valve and said plunger pump and between the latter and said second valve.

7. In apparatus of the type having means for supporting a pile of sheets to be fed one after another from the top thereof, and hydraulic mechanism including a cylinder for raising said pile supporting means, a pump and valve assembly comprising, a receptacle adapted to contain a supply of fluid, a housing in said receptacle and wholly submerged in the fluid therein, said housing having a fluid inlet port, a fluid outlet port and a fluid return port, a plunger pump in said housing and continuously reciprocated to draw fluid from said fluid supply into said housing through said inlet port and force said fluid therefrom into said cylinder through said outlet port and into said fluid supply through said return port, a pile controlled valve in said housing and disposed between said plunger pump and said fluid inlet port and reciprocal to connect the latter with and disconnect the same from said pump, a second valve in said housing and disposed between said plunger pump and said fluid outlet and return ports, said second valve being movable to one position to connect said plunger pump with said fluid outlet port and movable to another position to simultaneously connect said outlet port and said plunger pump with said return port, means for moving said second valve, check valves in said housing and disposed between said pile controlled valve and said plunger pump and between the latter and said second valve, and a pressure responsive relief valve in the housing and disposed between the plunger pump and said fluid outlet port.

8. In apparatus of the type having means for supporting a pile of sheets to be fed one after another from the top thereof, and hydraulic mechanism including a cylinder for raising said pile supporting means, the combination of a receptacle adapted to contain a supply of fluid, a housing in said receptacle and wholly submerged in the fluid therein, said housing having a fluid inlet port and two relatively spaced outlet ports, a conduit connected with said cylinder and with one of said outlet ports, a plunger pump in said housing and reciprocated to draw fluid from said fluid supply into said housing through said inlet port and force said fluid therefrom into said cylinder through said conduit, a slide valve in said housing and disposed between said plunger pump and said outlet ports, said valve being movable to one position to connect said plunger pump with said conduit and to close the other of said outlet ports and movable to another position to connect both said outlet ports and said conduit with said fluid supply, means for moving said valve, and a check valve in said housing and disposed between said plunger pump and said slide valve.
